VANITY CASE

Martine Kane, New York, N. Y., assignor to
 Helena Rubinstein, Inc., New York, N. Y., a
 corporation of New York

Application December 6, 1938, Serial No. 244,142

1 Claim. (Cl. 220—20)

This invention relates to improvements in vanity cases of the type embodying a plurality of compartments, which are hinged together to form a compact unit when closed, and which swing to open position to make the contents of each compartment readily accessible.

The object of my invention is to provide a vanity case comprising three compartments hinged together in such a manner that they are superposed in closed position to form a casing and in open position permit of bringing the bottom surfaces of the two outer compartments into a common plane, whereupon the third intermediate compartment is held in a position at right angles to said common plane, said third compartment being provided with a reflecting cover opening into a position at right angles to said common plane and to its own closed position.

I accomplish this object by means of a vanity case, one embodiment of which is described in the specification, set forth in the appended claim, and illustratively exemplified in the accompanying drawing, in which:

Fig. 1 is a perspective view of my improved vanity case, showing the compartments thereof in open positions;

Fig. 2 is a sectional view of one of the compartments and its hinge connection with the other compartments;

Fig. 3 is a sectional view of the vanity case in closed position.

Referring to the drawing, the vanity case comprises three compartments 10, 11 and 12, 10 and 12 being the outside compartments and 11 the intermediate or inner compartment. A vanity comprising compartments 11 and 12 is well known, the novelty of the present invention residing in the construction of compartment 10 and its combination with the other compartments 11 and 12.

Compartments 11 and 12 each comprise a square shaped frame having upstanding side walls 13 and closed face 14. The open faces of the two compartments 11 and 12 face each other and along the free edges forming one set of sides the latter are hinged together by means of a hinge connection 15. The interior of the compartments 11 and 12 may be arranged to accommodate powder, rouge and a double sided mirror cover 16 hinged to the compartment 11 on an axis at right angles to the hinge connection 15, the purpose of the construction being that when the two compartments are brought together they will form a more or less completely closed unit.

The third compartment 10 comprises an outside frame having upright sides 17 and outside wall 18, which corresponds to the face walls 14 of the other two compartments, and which carries a clasp 19 at its outer side wall to engage over the outer sides of the other compartments to hold the three compartments together in the closed position of the vanity. The compartment 10 is hinged to the compartment 11 by means of a hinge connection 20 arranged between the edge of the wall 17 and an off-set portion of the corresponding wall 13 at the corner thereof with the face 14. This arrangement of the three compartments enables the same to swing one over the other in superimposed positions to bring them to closed position, as illustratively exemplified in Fig. 3.

When the vanity is opened and the bottom faces 14 and 18 are placed on a horizontal support, the compartment 11 is held in vertical position and the outer mirror face of cover 16 presents itself to the user in a convenient vertical position. When the cover 16 is opened it swings on its hinge about a vertical axis into a position at right angles to its closed position, whereby the inner mirror or face of cover 16 presents itself to the user in a convenient manner.

Having now described my invention and the manner in which the same may be used, what I claim and desire to secure by Letters Patent is:

A vanity case comprising three compartments of substantially the same outline and being superposed in closed position of the casing with the surrounding side wall of the intermediate compartment constituting a portion of the outer wall of the casing and each of said compartments having an open top, a flat closed bottom and an upstanding surrounding side wall, the closed bottoms of the two outer compartments facing outwardly, two hinges connecting the top edges of the side walls of the two outer compartments to corresponding points at the top and bottom edges, respectively, of the third intermediate compartment, the hinge-carrying side walls of the outer compartments being so related and proportioned with respect to each other, that the bottom surfaces of said outer compartments can be brought into a common plane when the case is opened and the third intermediate compartment is then held rigidly in position at right angles to said common plane, and a mirror cover for said intermediate compartment hinged thereto on an axis at right angles to the hinges connecting the three compartments.

MARTINE KANE.
